(57) **CLAIM**

The ornamental design for a TV console with an adjustable extension, as shown and described.

DESCRIPTION

FIG. 1 is a top perspective view of a TV console with an adjustable extension, showing my new design with the extension shelf in a first position and the front piece in a right-most position;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is an exploded top perspective view thereof; and,

FIG. 9 is an alternate top perspective view thereof, illustrated with the extension shelf in a second position and the front cover in a central position.

The broken lines in the figures depict portions of the TV console with an adjustable extension that form no part of the claimed design.

1 Claim, 6 Drawing Sheets
